United States Patent Office

Des. 201,084

Patented May 11, 1965

201,084

BATTERY CHARGER

Franklin C. Bradshaw, 4319 NE. 7th St., Minneapolis,
Minn., and Terrance M. Smith, 354 E. Wheelock
Parkway, St. Paul, Minn.

Filed Sept. 3, 1964, Ser. No. 81,578

Term of patent 14 years

(Cl. D26—15)

The single figure is a left side, top and front perspective view of a battery charger, showing our new design. The right side is substantially a mirror image of the left side, and the back is substantially flat and unornamented.

We claim:

The ornamental design for a battery charger, as shown and described.
